US00D729765S

(12) **United States Design Patent**
Rivas(10) **Patent No.:** **US D729,765 S**
(45) **Date of Patent:** **** May 19, 2015**(54) **WIRELESS HEADPHONES**

(71) Applicant: **Marco Rivas**, Springfield, MA (US)
 (72) Inventor: **Marco Rivas**, Springfield, MA (US)
 (**) Term: **14 Years**
 (21) Appl. No.: **29/494,024**
 (22) Filed: **Jun. 17, 2014**
 (51) LOC (10) Cl. **14-01**
 (52) U.S. Cl.
 USPC **D14/205**
 (58) **Field of Classification Search**

FOREIGN PATENT DOCUMENTS

CN 2888595 4/2007

Primary Examiner — Paula Greene

(57) **CLAIM**

I claim the ornamental design for the wireless headphones, as shown and described.

DESCRIPTION

FIG. 1 is a front view of the wireless headphones.

FIG. 2 is a left side view of the claimed design.

FIG. 3 is a right side view of the claimed design.

FIG. 4 is a top view of the claimed design; and,

FIG. 5 is a bottom view of the claimed design.
